FRANK V. RISINGER, OF YOUNGSTOWN, OHIO, ASSIGNOR TO STEWART-WARNER SPEEDOMETER CORPORATION, OF CHICAGO, ILLINOIS, A CORPORATION OF VIRGINIA.

VACUUM-FEEDING DEVICE FOR CARBURETOERS.

Application filed July 6, 1920. Serial No. 394,339.

To all whom it may concern:

Be it known that I, FRANK V. RISINGER, a citizen of the United States, residing at Youngstown, in the county of Mahoning and 5 State of Ohio, have invented certain new and useful Improvements in Vacuum-Feeding Devices for Carburetors, of which the following is a specification, reference being had to the accompanying drawings, forming 10 a part thereof.

The purpose of this invention is to provide an improved device for supplying liquid fuel to the carburetor of an internal combustion engine from a main supply tank 15 at a lower level. It consists in the elements and features of construction shown and described, as indicated in the claim.

In the drawings:

Figure 1 is a vertical section axial with 20 respect to the principal chambers.

Figure 2 is a top plan view of the same.

Figure 3 is a detail section at the line

3—3, on Figure 2.

Figure 4 is a section at the line, 4—4, on 25 Figure 1.

In the construction shown in the drawings there are employed a pair of similar chambers, 1^a, 1^b, hereinafter referred to as the vacuum chambers. Each of these chambers 30 contains a float member, shown at 2^a, 2^b, respectively, mounted slidably on rods, 10^a and 10^b, respectively, which constitute the stems of valves, 3^a and 3^b, carried by said stems in the upper ends for closing suction 35 ports, 6^a and 6^b, formed in a cap plate, 6, which is common to both the chambers and which contains a suction passage, 6^x, common to both the vacuum chambers, that is, leading to both the suction ports, 6^a and 6^b, 40 and being itself extended for emerging through the port, 6^y, for connection with a source of suction by a pipe, not shown. Such source of suction may be, and in most usual practice will be, the intake manifold of the 45 engine which is to be served by the device. The cap plate, 6, has beside the suction ports, 6^a and 6^b, atmosphere inlets ports, 6^m and 6ⁿ, which are controlled by valves, 4^a and 4^b, respectively, said valves having their guide 50 stems extended through the ports, said ports being tapered and the valve heads being adapted to seat thereon at a distance back from the valve ports through which the stem extends some distance and for collision 55 with the floats, 2^a and 2^b, as hereinafter ex-

plained. Each of said chambers has a liquid supply connection, said connections leading from a source of liquid supply which may be understood to be a main fuel tank, not shown, which is at a lower level than the device shown in the drawings. For affording such liquid supply from the same source to both the chambers, 1^a and 1^b, the liquid conduit, 9, is a pipe having branches, 9^a and 9^b, leading to the two chambers respectively, and 60 in each of these branches there is provided, a check valve, 9^c, opening by flow of the liquid toward the chamber supplied, and adapted to be seated by any back flow from said chamber, thereby preventing flow of liquid 70 from either of said chambers into the other. In the suction passage, 6^x, common to the two chambers, there is positioned a lever, 11, fulcrumed midway between its ends and having connection at its opposite ends with the 75 stems, 10^a and 10^b, which carry the suction valves 3^a and 3^b, and on which the floats, 2^a and 2^b, are mounted for sliding a short distance between stops, 10^x and 10^y. Said stems 80 extend freely through the lever and are stopped thereabove by stop knobs, 10^v, by means of which the rods, 10^a and 10^b, are hung upon the opposite ends of the said lever, 11, so that while each suction valve is independent of the other in its seating movement to the extent that either can seat without operating the other, the contrary is true of the opening movement—that is, the downward or opening movement of either valve operating the lever, 11, tends to lift 90 the other suction valve.

The chambers, 1^a and 1^b, have in common a bottom plate, 15, in which are outflow passages 15^a and 15^b, for the chambers, 1^a and 1^b, respectively, said passages meeting at 95 15^m, and the outflow then continuing by a single passage, 15^m, in common to both chambers. At the junction of the passages, 15^a and 15^b, there is located a valve, 16, adapted to seat alternatively for closing either the 100 passage, 15^a or 15^b, being in position to be opened by outflow through either passage at which it is seated, and to be thrown by the outflow current over to the position for closing the other passage, and so that in case 105 of concurrent outflow through both passages it might be held at open position between the opposing currents. But in case of back-flow, it would be seated at one passage only and leave the other open to permit such backflow. 110

Below the bottom plate, 15, there is mounted a reserve fuel supply chamber, 18, into which the passage in common, 15^m, from the chambers, 1^a and 1^b, discharges, 5 said discharge passage being entirely free of any valve obstruction or the like. This reserve fuel supply chamber has a discharge connection shown at 18^a, by which the liquid contents of said reserve chamber 10 may be supplied to the carburetor by gravity flow. It will be noted that the arrangement of the valve, 16, seating at the passages, 15^a and 15^b, one at a time, leaving the other open, and the construction and mode 15 of operation of the suction and atmosphere valves of the chambers, 1^a and 1^b, insures that there shall always be atmospheric pressure operating either through one or the other of said chambers, 1^a, 1^b, and the out- 20 flow passages therefrom to the reserve fuel supply chamber, 18; so that outflow by gravity from the said chamber, 18, can occur at any time that there is liquid in that chamber to be discharged.

25 The mode of operation of this structure may be understood from the foregoing description, but may be further indicated in detail as follows:

Assuming the chambers to be both empty. 30 connections made from 6^x to a source of suction, and from the pipe, 9, to a source of liquid supply, both the suction valves, 3^a and 3^b, and both the atmosphere valves, 6^m and 6ⁿ, may be partly open; but the valve, 8 35 will be seated at the outflow port of one of the chambers, as for example, the chamber, 1^a, and the outflow port of the outer chamber, 1^b, will be open; and upon the admission of suction, the greater freedom of air 40 inlet through the chamber, 1^b,—air being freely admitted both past the air valves, 6^m or 6ⁿ, and through the liquid outlet passage of said chamber, 1^b,—will cause the suction valve, 3^b, of said other chamber, 1^b, to 45 be closed; and thereupon, suction operating in the chamber, 1^a, will cause it to fill with liquid lifted from the main low level supply chamber until the liquid level rises in said chamber, 1^a, so far as to lift the float, 2^a, 50 which will lift the suction valve, 3^a, so near to its seat that it will be pulled to its seat by the suction. In reaching its seat, the valve will pull the float a little above the level to which it has up to that point been 55 buoyed by the liquid, bringing it up against the lower end of the stem of the atmosphere valve, 4^b. If that valve is not thereby opened, the partial vacuum already existing in the chamber, 1^a, will cause the further 60 continuous inflow of liquid to a certain extent, further buoying the float, 2^a, sufficiently to enable it to force the air valve, 4^b, off its seat against the slight resistance of the springs, 10^x, interposed below the stop, 10^x, 65 and the resistance of the atmosphere due to to the partial vacuum still remaining in the chamber, 1^a, the rise of the float upon breaking the suction hold of the air valve, being sufficient to carry that valve an adequate distance away from its seat to permit substantially unobstructed entrance of atmospheric pressure to cause the discharge of the liquid by gravity from the chamber, 1^a, which will reverse the position of the valve, 16, throwing it over in position to close the liquid outflow passage from the chamber, 1^b. 70 Also the rise of the valve, 3^a, to its seat freeing the lever, 6^x, will leave the valve, 3^b, free to descend, as it will do at once upon the operation of the full unsupported weight 75 of the float, 2^a; whereupon the air valve, 6^a, moving to closed position, suction being operative to produce partial vacuum in the chamber, 1^b, that chamber will become filled with liquid while the chamber, 1^a, is emptying, and the operations above described with respect to the chamber, 1^a, will be repeated with respect to the chamber, 1^b; and alternation of these two operations between the two chambers will continue until the 80 fuel reserve chamber, 15, becomes filled and the liquid rises first in the chamber, 1^a or 1^b,—whichever happens at that time to be in process of filling—to the float-operating level; and upon the reversion of the valves 85 above described, shifting the suction to the other chamber, that chamber will be filled, the first filled chamber in the meantime remaining filled because it can no longer discharge into the already filled fuel reserve 90 chamber, 15; and thus eventually, not only the fuel reserve chamber but both the chambers, 1^a and 1^b, will be filled to the float-operating level; and thereupon the device will 95 cease to operate until the flow of liquid from the fuel reserve chamber for supplying the engine permits the vacuum chamber whose outflow passage happens to be open, to become emptied so far as to cause its float to operate by its weight to open the suction 100 valve, admitting the suction for filling that chamber, while, if there is still unfilled capacity in the fuel reserve chamber, the other vacuum chamber is emptying; and the cycle of operation as above described is 105 thus resumed, and continued so long as there is maintenance of suction and unfilled capacity in the reserve chamber.

It should be noted that whereas, in the initial operation of the device, starting from 110 the condition of emptiness of all chambers, the full weight of the float in the second vacuum chamber to be filled is operative for reversing the valve situation as soon as the liquid rises in the first filling chamber so as 115 to buoy the float therein, the situation is not identically the same in subsequent operation, because it may happen that the liquid level has not receded in the chamber which was first filled, so as to completely unsubmerge 120

the float therein, that is, to leave it entirely above the liquid and its whole weight operative,—by the time the liquid has risen in the other chamber so as to reach and begin 5 to buoy the float; the parts are so proportioned that the valves will be operated as described against the suction tending to hold them on their seat against their weight, by the co-operation of the two floats, the operative weight of one to the extent that it is 10 unsubmerged being assisted by the buoyancy of the other to the extent that it is submerged.

The purpose of the light coiled springs, 15 18, 18, interposed between the floats, 2^a and 2^b, and the upper stops on the stems, 10^a and 10^b, is primarily and chiefly to prevent disturbance of the position of the suction valves, 3^a and 3^b, by the jarring of the device in travel.

It will be observed that under conditions of high suction and small consumption of fuel by the engine, causing rapid inflow of liquid and limited outflow, the reserve 25 fuel supply chamber, 18, may become filled the liquid rising in the vacuum chamber to the high liquid level indicated by the line, X—X, on Figure 1. If under such conditions, or under any conditions in which the 30 reserve fuel supply chamber is filled and there is liquid in one or the other or both of the vacuum chambers, the device becomes over-heated to the boiling point of the liquid, all danger of discharge of the gaso- 35 line by boiling and expansion is prevented by reason of the fact that vapor or liquid

expansion from all the chambers will find free accommodation, one or the other of the outflow passages to the reserve fuel chamber being open for back-flow into one or the 40 other of the vacuum chambers, and the air valve, 4^a or 4^b, of that chamber, being open to permit the escape of vapor from the top of the liquid in that vacuum chamber into which the contents of both the other chambers of the device can expand freely.

I claim:

In a device for the purpose indicated, a pair of chambers having a suction connection in common and a passage to which the 50 suction connection is made: suction ports for the two chambers respectively, opening into said passage; valve means in said chambers controlling said ports respectively for causing alternate dominance of suction and 55 air pressure in the chamber; outflow connections from the chambers respectively, comprising a passage in common; valve means in said outflow connection adapted to be opened by liquid outflow from and held seated by 60 suction in the respective chambers, and means situated in said suction passage in common for correlating the action of the first mentioned valve means in the chambers for reversely operating the corresponding 65 valves of the two chambers by the same movement.

In testimony whereof, I have hereunto set my hand at Chicago, Illinois, this 16th day of June, 1920.

FRANK V. RISINGER.
